UNITED STATES PATENT OFFICE.

WILLIAM HENRY COOK, OF NEWARK, DELAWARE.

DEVICE FOR OPENING OR CLOSING TROLLEY-CAR DOORS.

SPECIFICATION forming part of Letters Patent No. 722,422, dated March 10, 1903.

Application filed December 9, 1902. Serial No. 134,562. (No model.)

To all whom it may concern:

Be it known that I, WILLIAM HENRY COOK, a citizen of the United States, residing at Newark, in the county of Newcastle and State of

5 Delaware, have invented certain new and useful Improvements in Devices for Opening and Closing Trolley-Car Doors, of which the following is a specification.

This invention relates to automatic devices 10 for opening and closing doors, whereby the opening or closing of the door is effected by a system of levers operated by foot-power.

The invention is particularly adapted for use in connection with sliding doors, and in 15 the present case is illustrated as applied to the doors of a car; but it is to be understood that the invention is not limited in its application to cars only.

The invention will be fully described here- 20 inafter, reference being had to the accompanying drawings, in which—

Figure 1 is an end elevation, partly in section, of a street-car, showing my invention applied thereto. Fig. 2 is a vertical longitudi- 25 nal section of a portion of a street-car.

In the present case I have illustrated two sliding doors A, supported by rollers a, attached to their upper ends, which rollers run upon a track b.

30 Referring now to the drawings, there are two sliding doors A, supported by rollers a, attached to their upper ends, which rollers run upon a track b.

35 The floor of the car is indicated by i, and an opening is cut in said floor, preferably near the dash C, to receive a rocking plate y, which is provided with pivots h, supported in suitable bearings in the floor.

40 Suspended from the under side of the car-floor are a plurality of hangers or brackets m, which form bearings for a horizontally-extending rock-shaft f, and near one end this shaft is provided with a laterally-extending 45 arm k, rigidly connected thereto, and the outer end of the arm is connected by a link o to the rocking plate y on one side of its pivot, so that when the plate y is rocked by pressure applied to it on either side of its pivot the 50 shaft f will also be rocked. The shaft f is also provided with two arms L, rigidly connected to it, and these arms extend in oppo-

site directions from the shaft f and may be integral or separate. The arms L are preferably arranged vertically and will oscillate 55 when the shaft f is rocked.

d d are two levers pivoted, respectively, to a fixed part of the car at or adjacent to the floor thereof, and the lower short arms of the levers are connected, respectively, by 60 links p to the respective arms L. The long arms of the levers d are respectively connected at their upper ends to the edges of the respective doors A by links e.

When the doors A A are closed, the rock- 65 ing plate y and the lever and link connec- tions between it and the doors will occupy the positions shown by full lines in Fig. 1. If pressure be applied to the plate y, as by a per- son stepping on it on that side of its pivot to 70 which the link o is connected, the plate will rock or tilt, and thereby rock the shaft f and oscillate the arms L, and the levers d will be operated to open the doors A. The positions of the several parts when the doors are open are 75 indicated by dotted lines in Fig. 1. To close the doors, it is only necessary to apply pres- 80 sure to the plate y on the other side of its pivot. This arrangement of devices will not interfere with opening and closing the doors 85 by hand, but, on the contrary, will transmit movement from one door to the other, so that if one door is moved to open or close it the lever and link connections will transmit movement to the other door and open or close it, as the case may be, to a corresponding ex- 90 tent.

If only one door is to be operated, one each of the levers d, arms L, and links p and e will be dispensed with.

95 This invention when applied to a car will enable the conductor to open and close the doors by foot-pressure on the plate y without having to move from his position at the rear end of the car, and the devices will not interfere with opening the door by hand when de- 100 sired.

Without limiting myself to the precise details of construction illustrated and de- 105 scribed, I claim—

1. The combination with a sliding door, of a rocking plate pivotally supported near the door, a rock-shaft supported below the plate and having a laterally-extending arm, a link

connected at one end to said arm and at its other end to said plate on one side of its pivot, an arm L rigidly connected to said shaft and a pivoted lever connected at one end to the door and at the other end to the arm L, substantially as set forth.

2. The combination with a sliding door and a floor below it, of a rocking plate pivotally supported in an opening in the floor, a rock-shaft supported in bearings below the floor and having a laterally-extending arm, a link connected at one end to said arm and at its other end to the plate on one side of its pivot, another arm rigidly secured to the rock-shaft 10 and extending in a vertical direction therefrom, a pivoted lever, a link connecting the lower end of the lever to the vertically-extending arm, and a link connecting the upper end of the lever to the door, substantially as set forth.
- 15 3. The combination with two sliding doors

and a floor below them, of a rocking plate pivotally supported in an opening in the floor, a rock-shaft journalled in bearings below the floor and having a laterally-extending arm, a link connecting said arm to the rocking plate on one side of the pivot of the latter, two vertically-disposed oppositely-extending arms rigidly connected to said shaft, a pair of levers d pivotally supported and 20 their upper ends respectively connected to the respective doors, and links connecting the lower ends of the levers to the outer ends of the vertically-disposed arms, substantially as set forth.

In testimony whereof I have signed my name to this specification in the presence of two subscribing witnesses.

WILLIAM HENRY COOK.
